UNITED STATES PATENT OFFICE

92,332

DESIGN FOR A COAT

Julius Baron, Brookline, Mass., assignor to Baron
Dress Company, Boston, Mass.

Application April 18, 1934, Serial No. 51,444

Term of patent 3½ years

To all whom it may concern:

Be it known that I, JULIUS BARON, a citizen of the United States of America, residing at Brookline, in the county of Norfolk, State of Massachusetts, have invented a new, original, and ornamental Design for a Coat, of which the following is a specification, reference being had to the accompanying drawing, forming a part thereof.

Fig. 2 is a rear elevational view thereof.

I claim:

The ornamental design for a coat substantially as shown.

In testimony whereof I have signed this specification.

JULIUS BARON.
